INTERLOCKING MEANS FOR THE MARGINAL EDGES OF SUPERIMPOSED SHEETS

Charles W. Sadenwater, Saginaw, Mich., assignor to National Washboard Company, Chicago, Ill., a corporation of West Virginia

Application July 30, 1934, Serial No. 737,484

4 Claims. (Cl. 68—29)

This invention relates to edge-binding or locking means for two sheets of material that is foldable, bendable, or ductile, such as metal or the like, in flatwise engagement, at least one of said sheets being corrugated. Such structures are useful in various and sundry arts, and my invention in its broader aspects is to be so considered; but for the purpose of pointing out the novel features of my improvement it will be here described as it appears when applied to the rubbing surfaces of washboards having two rubbing faces made of two metal sheets each corrugated so as to present alternating ridges and channels, the two sheets being placed face to face so that points on the top surfaces of their ridges are contiguous, the ridges of one sheet being disposed in criss-cross arrangement with respect to the ridges of the other sheet so that each rib of one sheet serves as a transverse support for all of the several ribs of the other sheet.

Wash-boards of such type are described and claimed in an application copending herewith, Serial No. 724,700; filed May 9, 1934 by Charles T. Gilbert, and owned by a common assignee of record.

In that application there is also shown and described a wash-board wherein the lateral edges of the two corrugated rubbing sheets are first flattened and then secured together so as to unite the two sheets into a unitary double-faced rubbing element, one face of which has horizontally disposed ribs and channels, the other vertical.

My present invention in the embodiment herein described pertains to a new and improved means for securing together the edges of two such corrugated rubbing sheets, although the edges of one sheet retain their original corrugated form, that is, they are not flattened.

The objects are, to impart to such a combined unitary rubbing face structure a greater degree of rigidity and strength, with less vibration of the sheets when in use and consequently less noise.

I attain the advantage of greater rigidity by a novel interlocking structure of the marginal edges of one of the two sheets, whereby the bottom portion of the trough of each corrugation of one sheet is individually fastened to the non-corrugated marginal edge of the other sheet in such a way as to hold all of the said corrugations in their proper spaced relation, and thereby prevent creeping when in use.

With the foregoing and certain other objects in view, which will appear later in the specifications, my invention comprises the devices described and claimed and the equivalents thereof.

Figs. 1 and 2 are diagrammatic face views of the two rubbing elements.

Fig. 3 is a fragmentary detail view showing my improved means for fastening together the contiguous edges of sheets such as shown in Figs. 1 and 2.

Fig. 4 is a sectional detail view on line 4—4 of Fig. 3.

Fig. 5 is an edge view of the parts shown in Fig. 4, as they appear when seen in the direction of the arrow, before the marginal edges of the two sheets are interlocked.

Fig. 6 is a sectional view, partly broken away, showing a wash-board embodying my improvement in a modified form.

In making a rubbing element according to the illustrated embodiment of my invention I provide two corrugated sheets 1, 2 of such relative size that when the sheets are laid one upon the other in the positions indicated by the dotted lines in Figs. 1 and 2, and in Fig. 4, the flat edges 1a, 1a, of sheet 1, parallel with the ribs 1b, project beyond the edges 2c of the other sheet 2, and the edges 2a, 2a of sheet 2 will likewise project beyond the edges 1c, 1c of sheet 1. These projecting portions, for example the part 1a, indicated in Fig. 4 by dotted lines, are bent at right angles so as to present a flange 3 whose width is preferably about equal to the height of the ribs 2b of sheet 2.

Portions 3a of the free edges of the flange 3 extend across the spaces between successive ribs 2b. They are bent inwardly and downwardly into the position indicated at 4, Figs. 3 and 4. Intermediate portions 3b of the flange are not bent. They form end wall abutments for the ribs 2b. The part 3a when bent as described conforms with the shape of the wall of channel or trough 2d and acts as a retaining ferrule or tang to lock each rib 2b against slipping, creeping or springing sidewise, endwise or up-and-down with respect to the opposite sheet. The rigidity of both sheets 1, 2 is greatly increased by the above described interlocking arrangement and lighter and cheaper sheets can be used than would be permissible otherwise.

In some types of wash-boards it is advisable to provide on the assembled rubbing unit marginal edges of appropriate shape and thickness to be received as a close fit in grooves of standard width which are provided in the wash-board frame members 5, 6, in the manner shown in Fig. 6. In such cases a slightly modified form of flange 3 is used, there being an additional flange portion 7 on sheet 2 that laps over the faces of

the ribs 1b of the opposite sheet 1. Here flange 3 serves as a complete closure for the ends of the corrugations 1b beside preventing endwise movement of sheet 1, but they are not bent inwardly, as in the form shown in Fig. 3. Instead, flanges 3 and 7 enfold the end of corrugated sheet 1 and present a tenon-like edge to be received in the mortise-like groove of the wash-board frame. The edges 7a of the flange portions 7 can be bent down so as to fit into the troughs between ribs 2b, thereby locking the sheets against creeping, in the same manner as shown at 4 in Figs. 3 and 4. Even the hardest rubbing to which a wash-board is normally subjected in use does not spring, stretch or distort the corrugations of the two sheets when fastened together in the manner above described. It prevents each sheet from rattling against the opposite backing sheet. Moreover, the marginal edge of one sheet provides an abutment wall for the end of the corrugations of the other sheet, greatly increasing the strength and rigidity of the assembly.

The great degree of marginal rigidity of the unitary structure characterized by my improvement renders it feasible to use lighter sheets without impairing either the working strength or the stiffness of the completed rubbing element.

For purposes of description I have shown the corrugated sheets with smooth ridges and furrows in Figs. 1, 2, 3, 5, and 6, and with embossed ridges in Fig. 4, but my claimed invention is adapted to be used with any type or form of ridged, ribbed, or fluted sheets having ridges of any suitable or usual type, plain or embossed.

While I have shown and described both sheets as being corrugated, it is obvious that one of them may be non-corrugated. For example, the corrugations, 1, Fig. 3, may be omitted without departing from the invention as set forth in certain of the claims.

Having thus described my invention, what I claim and desire to secure by Letters Patent is:

1. In a wash-board rubbing element wherein two corrugated sheets of ductile material are su-

perimposed in flatwise engagement with their respective ridges and furrows lying in relatively criss-cross arrangement and in contact for mutual support, in combination, flanges on opposite edges of one of said sheets parallel with the corrugations thereof, said flanges presenting abutments in engagement with the ends of the corrugations on the other sheet, spaced-apart portions of said flanges projecting into the ends of the furrows on said other sheet and engaging the walls of said furrows, to secure the individual corrugations of each sheet against tendency to creep relatively to the other sheet under the conditions of use of the rubbing element.

2. The invention as set forth in claim 1 wherein the spaced-apart portions of said flange are elongated and wide and are shaped to fit closely the walls of the said furrow over an appreciable area, in the manner of a ferrule.

3. In a wash-board rubbing element wherein two corrugated sheets of ductile material are superimposed with their respective ridges and furrows lying in relatively criss-cross arrangement and in contact for mutual support, in combination, flanges on opposite edges of one of said sheets parallel with the corrugations thereof, said flanges presenting abutments in engagement with the ends of the corrugations on the other sheet, portions of said flanges enfolding the ends of the corrugations on said other sheet and engaging the same, edges of said flange portions being bent down into the furrows to grip the other sheet and to prevent movement of one sheet relatively to the other.

4. A securing means for sheets of ductile metal or the like in flatwise engagement, one having elongated corrugations spaced apart and presenting furrows terminating at the edge of the sheet, said securing means comprising tangs on the edge of the other sheet at the ends of the furrows, said tangs extending over upon and into the respective furrows and lockingly engaging therewith in substantially ferrule-like manner.

CHARLES W. SADENWATER.
